UNITED STATES PATENT OFFICE.

JOSEPH F. PUNZAK, OF BROOKLYN, NEW YORK.

DESIGN FOR A COIN BANK.

Application filed August 5, 1926. Serial No. 18,593. Term of patent 14 years.

To all whom it may concern:

Be it known that I, JOSEPH F. PUNZAK, a citizen of the United States, residing in the city of New York, borough of Brooklyn, in the county of Kings and State of New York, have invented a new, original, and ornamental Design for Coin Bank, of which the following is a specification, reference being had to the accompanying drawings, forming a part thereof.

Figure 1 is a top or plan view of the coin bank and Fig. 2 is an end view of that end containing the opening for the insertion of the coins, showing my new design.

I claim:

The ornamental design for a coin bank as shown.

JOSEPH F. PUNZAK.
